UNITED STATES PATENT OFFICE.

CHARLES MARIE VON EUGEN AND HARRY LETCHFORD, OF COVENTRY, ENGLAND.

CONSTRUCTION OF WINGS AND THE LIKE FOR AERIAL MACHINES.

1,281,442.

Specification of Letters Patent. Patented Oct. 15, 1918.

Application filed November 21, 1917. Serial No. 203,129.

To all whom it may concern:

Be it known that we, CHARLES MARIE VON EUGEN, a subject of the Queen of Holland, and HARRY LETCHFORD, a subject of the King of England, both residing in Coventry, Warwickshire, England, have invented certain new and useful Improvements in the Construction of Wings and the like for Aerial Machines, of which the following is 10 a specification.

Our invention relates to the manufacture of wings and the like for aeroplanes, and similar parts, such as balancing planes, elevators, and the like, as used on aeroplanes 15 and air-ships, and it has for its object to provide a strong and light construction which will be non-inflammable, incapable of warping, and simple to manufacture.

The invention comprises the combination 20 of spars, tubular or composed of two combined channel members, ribs which taper fore and aft and are provided with sinuous webs of which the peaks of each of the bends are connected alternately to the upper and 25 lower plates of the rib, an edging of tubing or U-shaped metal strips, and a covering preferably of sheet metal.

The channel members forming the hollow spars can be arranged either back to back 30 or one inside the other. The ribs can be curved to follow the curvature of the wing section. The bends of the sinuous web are connected alternately to the upper and lower plates of the rib preferably by flanges 35 formed at each of the bends, while the web may be grooved or corrugated to afford additional strength.

In the accompanying drawings:—

Figure 1 is a plan of a supporting plane 40 for an aeroplane:

Fig. 2 is a section on the line 2—2 in Fig. 1, showing the construction of a rib.

Fig. 3 is an elevation of a spar.

Fig. 4 is a transverse section through a 45 main compression rib, while

Fig. 5 is a section through a secondary rib.

Figs. 6 and 7 are respectively an elevation and a plan showing the connection of 50 a rib to a spar.

Figs. 8 and 9 are respectively a vertical and a horizontal section through a rear spar.

Figs. 10 and 11 are respectively a vertical section and a plan of a spar showing a 55 method of attaching eyes or other parts.

Figs. 12 and 13 are sections through the leading and trailing edges respectively, showing the method of finishing off these 60 parts.

Fig. 14 is a vertical section through an end rib.

Fig. 15 is a section showing how a joint may be effected between two planes or between two parts of a single plane. 65

Fig. 16 is a section on the line 16—16 in Fig. 15.

Fig. 17 is a plan of the construction shown in Fig. 15.

Fig. 18 is a horizontal section through the 70 end of a spar.

Fig. 19 shows a method of connecting a bottom plane to a fuselage, mast or the like.

Figs. 20 and 21 are respectively a vertical 75 and a horizontal section showing the construction of a spar formed as a box girder.

Like letters indicate like parts throughout the drawings.

In the construction illustrated, the front 80 edging A and rear edging B and the spars C and D are connected by main compression ribs E and secondary ribs E². The ribs are formed of an upper plate F and a lower plate G joined by a sinuous web H which 85 in the case of main ribs is double as shown in Fig. 4, while for the secondary ribs a single strip is employed, see Fig. 5. In both cases the sinuous strips are corrugated to afford stiffness and are provided with flanges 90 H² at each of the bends to connect alternately to the plates F and G.

The spars C, D, are formed of metal of channel section riveted or bolted back to back as shown at C² in Fig. 6 and having 95 their edges turned over for stiffness; and the holes in their web portions may be flanged over for the same purpose. Further, plates or strips of metal C³ (see Figs. 6 and 8) may be placed over the adjoining 100

flange portions of the channels and riveted in place, while the webs may be formed to receive register rings J as described in our co-pending British application No. 16717 5 of 1916. Figs. 6 and 7 also show the method of attachment of the ribs to the spars. The ribs are provided with apertures conforming to the section of the spars enabling them to be threaded over the spars and angle pieces 10 C³ are attached to the ribs, and then bolted up to the web of the spar, packing pieces being inserted at C⁴ to afford firm support for the attachment bolts.

Figs. 8 and 9 illustrate a portion of a rear 15 spar at the point where no trailing edge proper is employed. At such a point it may be desirable to arrange for a pivotal support for an aileron or other member, and this may be effected by adapting the registering ring J to receive a hinge member K. The edge of the spar is then closed by a plate L, which is perforated to pass over the hinge member K.

In Figs. 10 and 11 is illustrated a construction for attaching any desired parts to the spars. For instance, the parts to be attached may be levers, struts, or wiring plates, but the drawings illustrate simple eyes M, by way of example only. It will be seen that the spar is drilled preferably on either side of a rib and the pieces M are secured in position by bolts N. Threaded upon the bolts are ferrules O, which fit snugly between the flanges of the spar. 35 Packing pieces P may be employed where required, and upon tightening up the bolts it will be clear that the compression strain is taken by the ferrules so that the spar and rib are not distorted. Further, by staggering 40 the bolts, as illustrated, the spar is not weakened unduly in any one direction.

Referring to Figs. 12 and 13, the edging O² is of metal tube which may be reinforced with a core of cane O³. This tube is inclosed 45 by the rib plates F and G. The covering material is then put into position and the edging is completed by superposing a U-shaped strip held in position by screws O⁴.

The covering throughout is preferably 50 of this sheet metal, indicated by X in the various views, secured in position by rivets or screws having countersunk heads which grip a comparatively large area of the covering material. In Fig. 14 is shown an end 55 rib which is closed by a plate R which, at the same time, secures the covering material.

Figs. 15, 16, and 17 illustrate how a joint 60 may be effected between a main plane and a central plane, or between two parts of a single plane. It will be seen that at the point of attachment the planes are provided on the upper and lower faces with hinge members S which are secured to the spars by bolts S², ferrules being inserted as described

with reference to Figs. 10 and 11. The position of the joint is such that the planes abut firmly together, and when the hinge pins are inserted a firm joint is obtained. The hinge is not actually intended to afford a pivotal joint but affords a convenient method of 70 construction.

Fig. 18 illustrates how the end of a spar may be finished off, particularly where a butt joint is to be located at this point. The channel pieces have their flange portions removed for a short distance and the webs are then turned over to close the ends of the channels. A plate Y is then placed over the end and secured in position by rivets or the like.

Fig. 19 illustrates the method of attachment of a wing to the fuselage, or a mast in the case of a monoplane. It will be seen that the end of the spar is embraced by a yoke T upon which is mounted one member T² of 85 a ball-and-socket joint, the other member of which is attached to the fuselage or other part.

In Figs. 20 and 21 there is shown a construction of box girder for employment in 90 the case of a wing flap or elevator spar. This comprises two dished elements U, U² fitting one within the other, and passing between the upper and lower plates of the ribs. The parts are then secured by riveting and 95 bolting, the covering being secured at the same time. A hinge member V may also be attached to the dished members and to flanges formed at the ends of a sinuous web serving to brace the structure.

What we claim as our invention and desire 100 to secure by Letters Patent is:—

1. A metal wing or supporting plane or the like for aerial machines, comprising hollow spars, ribs tapering fore and aft and 105 each composed of an upper and a lower plate and there between a continuous sinuous web having the peaks of each of its bends connected alternately to the said upper and lower plates, an edging of metal tube, and a 110 covering of sheet metal.

2. A metal wing, as specified in claim 1, in which the hollow spars are composed of two channel members secured together.

3. A metal wing, as specified in claim 1, in 115 which the edging consists in a U-shaped metal strip, and a covering of sheet metal.

4. A metal wing, as specified in claim 1, in which the continuous sinuous web is corrugated to increase its stiffness.

5. A metal wing or supporting plane or the like for aerial machines, comprising hollow spars; ribs tapering fore and aft and each composed of an upper and lower plate, and there between a continuous sinuous web having the peaks of each of its bends connected alternately to the said upper and lower plates, and having flanges at its bends for

connection to the said plates, a separate edging, and a covering of sheet metal.

6. A metal wing or supporting plane for aerial machines, comprising hollow spars, 5 ribs tapering fore and aft and each composed of an upper and lower plate and there-between a corrugated continuous sinuous web having the peaks of each of its bends connected alternately to the said upper and 10 lower plates, and edging consisting in a U-

shaped metal strip, and a covering of sheet metal.

In testimony whereof we have signed our names to this specification in the presence of two subscribing witnesses.

CHARLES MARIE von EUGEN.
HARRY LETCHFORD.
